(57) **CLAIM**

The ornamental design for a toy flower as shown and described.

DESCRIPTION

FIG. 1 is a front, top, right side perspective view of a toy flower showing our new design;

FIG. 2 is a rear, bottom, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view taken along line 9-9 of FIG.

7.

The broken lines in the drawings are for the purpose of illustrating portions of the toy flower that form no part of the claimed design.

1 Claim, 9 Drawing Sheets
